UNITED STATES PATENT OFFICE

2,283,051

PORTABLE DRY CONCENTRATOR

Charles M. Fuller, Lodi, Calif., assignor to
E. D. Wilkinson, Stockton, Calif.

Application January 15, 1940, Serial No. 313,877

1 Claim. (Cl. 209—475)

This invention relates to dry concentrators and particularly to one of a small portable size such as may be operated by hand or a small motor, and thus is suitable when a relatively small quantity of material is to be handled for concentration.

The principal object of the present invention is to provide a concentrator of the above type which, while utilizing positive and negative pressure as the concentrating means, in the same manner as covered in my United States Patent No. 2,148,068, creates such pressures by a single hand or small power operated means instead of by the separate large power driven instrumentalities necessary with the structure of the patent.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claim.

In the drawings similar characters of reference indicate corresponding parts in the several views:

Figure 1 is a side elevation of the portable concentrator.

Figure 2 is a sectional elevation of the structure.

Figure 3 is a top plan of the concentrating table partly broken out to show the structure immediately below.

Figure 4 is a cross section on line 4—4 of Fig. 2.

Figure 5 is an enlarged fragmentary section showing the concentrating table before being lowered to cooperating relation with the structure below.

Figure 6 is a side view partly in section of a concentrator having a modified form of pressure creating means.

Referring now more particularly to the characters of reference on the drawings, and particularly at present to Figs. 1 to 5, the concentrator comprises a table having side rails 1 between which, at the ends, are plates 2, with spaced riffles 3 between the plates. The plates and riffles are flush with the lower surface of the rails and are shallow relative to the depth of the rails. The riffles are concaved from the bottom up, on one side as clearly shown. The under side of the table is covered throughout its extent with a length of taut foraminous fabric such as muslin 4, which is tacked or otherwise secured on the rails and end plates.

The table rails and end plates removably rest

on the matching side bars and end plates 5 and 6 respectively of the stationary supporting structure; side boards 7 upstanding from the bars 5 along their outer side edges and for their full length to a height well above the table. Bars 6 are supported at a predetermined slope from end to end by corner legs 8. The table thus has a corresponding slope; the riffles being disposed so that their concave sides face upwardly of the slope.

Upwardly facing channels 9 forming transverse grate elements extend between bars 5 directly under the riffles with their upper edges flush with the upper surface of the bars; these channels being filled with strips of felt 10 which initially project above the channels somewhat, as shown in Fig. 5. The table supporting structure, which includes bars 5, plates 6 and channels 9, is covered throughout its extent with fine wire screening 11, which acts as a reinforcing for the muslin above.

The table is held down on the supporting structure, so that it cannot slide and so that the riffles compress the felts, by suitable means such as cam levers 12 mounted on the side walls 7 adjacent their ends. This compression of the felts insures a tight contact of the muslin with the bottom of the riffles, preventing any fine concentrates from filtering under the riffles.

The table supporting grate which includes bars 5, plates 6 and channels 9, forms the top of an air pressure or wind chamber 13, which includes side boards 14 depending from the bars 5 at their outer edges and for their full length. The bottom of this chamber is formed by an oscillating bellows board 15, pivoted as at 15a at the lower end of the chamber in such a position that it may move to an adjacent and parallel relationship with the table.

The board is oscillated through a stroke of predetermined length by means of a link 16 extending between the under side of the board and an arm 17 projecting lengthwise of the board from a transverse shaft 18 supported from brackets 19 mounted on the side walls 14.

Secured on and upstanding from the shaft 18 at one end outwardly of the air chamber is another arm 21, connected by a side rod 22 with a flywheel 23 in offset relation to the axial shaft 24 thereof. This shaft is supported from the legs 8 at the high end of the apparatus, and is rotated from a shaft 25 parallel to and above said shaft 24, and which has a crank handle 26 on one end and at the other end is connected to shaft 24 by a belt drive 27. The shaft 24 may of course

be driven by a motor instead of by hand as described.

The link 16 may be connected to the board 15 and arm 17 at varying points in their length, and likewise the rod may be connected to arm 21 and the flywheel at varying distances from their axial shafts. In this manner it is possible not only to alter the length of the stroke of the bellows board, but the point of nearest approach of the board toward the concentrating table may be altered independently of the length of the stroke. As a result air pressures, both positive and negative, of varying intensities, may be created in the pressure chamber to act through the foraminous fabric of the bottom of the table on the concentrates and thus giving the same concentrating action as is obtained with the power operated structure of my aforementioned patent.

The velocity of the air movement through the fabric is accentuated without any very large bellows movement being necessary by reason of the fact that the side bars 5 and bottom plates 6 as well of course the cross channels 9, restrict the area of the opening through the table relative to the corresponding area of the chamber considerably.

With the above arrangement, the speed of the down (suction) stroke of the bellows board is of course the same as that of the up stroke (pressure stroke) of the board. Under certain conditions, for a better concentrating action, it may be found desirable to increase the velocity of the air on the suction stroke relative to the pressure stroke. To obtain such an action the bellows may be operated as shown in Fig. 6. In this structure, the bellows board 15a is connected to a depending rod unit 28 engaged for vertical movement by guides 29 mounted on the frame of the machine.

A strong tension spring 30 is applied to the rod 40 to pull the same down, and said rod is raised a certain distance against the resistance of the spring by means of a rotary transverse shaft 31 mounted on the frame to one side of the rod 28

and driven from the operating handle 26a by a belt drive 27a. An arm 32 projects radially from the shaft 31 and carries a cam roller 33 on its outer end which engages for a portion of the upward swing of the arm under a lug 34 adjustably mounted on the rod 28. The roller as it moves up thus lifts the rod and bellows a distance depending on the setting of the lug on the rod, and then suddenly moves from under said lug, so that the expanded spring 30 is then free to pull the rod and bellows sharply down. A suctional action through the fabric of the concentrating table, of greater intensity than the upward pressure stroke, is thus created.

15 From the foregoing description it will be readily seen that I have produced such a device as substantially fulfills the objects of the invention as set forth herein.

20 While this specification sets forth in detail the present and preferred construction of the device, still in practice such deviations from such detail may be resorted to as do not form a departure from the spirit of the invention, as defined by the appended claim.

25 Having thus described my invention, what I claim as new and useful and desire to secure by Letters Patent is:

30 A dry concentrator comprising means forming an air pressure chamber open to the top, a concentrating table having a bottom pervious to air mounted over and closing the top of the chamber, a bellows element forming the bottom of the chamber, means pivoting the element at one end for oscillating movement toward and from the table, a transverse oscillatory shaft disposed intermediate the ends of the element, a radial arm projecting from the shaft and substantially parallel to the element, a link connected at one end to the arm at different selected points in the length thereof, and means connecting the link at its other end to the bellows element at different selected points in the length thereof.

CHARLES M. FULLER.
